ROOF OR THE LIKE

Henrik H. Bull, San Francisco, Calif., assignor to California Redwood Association, San Francisco, Calif.

Filed Dec. 27, 1966, Ser. No. 5,177

Term of patent 14 years

(Cl. D68—1)

FIG. 1 is a side elevational view of the roof;

FIG. 2 is an end elevation of FIG. 1;

FIG. 3 is a top plan view of FIG. 1;

FIG. 4 is an expanded fragmentary view taken from above and perpendicular to the roof at the area enclosed by line 4 of FIG. 3;

FIG. 5 is a fragmentary end view of FIG. 4;

FIG. 6 is an end elevation of a roofing member;

FIG. 7 is a fragmentary top plan view of FIG. 6;

FIG. 8 is a fragmentary side elevational view of FIG. 6; and

FIG. 9 is a fragmentary bottom plan view of FIG. 6.

It is to be understood that the portions shown in full lines in FIGS. 1 and 3 continue throughout the broken line portion of the roof. The broken line showing of a building side walls in FIGS. 1 and 2 is for illustrative purposes only.

I claim:

The ornamental design for a roof or the like, as shown and described.
